UNITED STATES PATENT OFFICE.

JOHN D. CROUCH, OF NEW YORK, N. Y.

TRUNK.

SPECIFICATION forming part of Letters Patent No. 339,622, dated April 13, 1886.

Application filed January 11, 1886. Serial No. 188,210. (No model.)

To all whom it may concern:

Be it known that I, JOHN D. CROUCH, of New York city, New York, have invented a certain new and useful Improvement in Trunk-Boxes, of which I declare the following to be a full, clear, and exact description, reference being had to the accompanying drawings, and to the letters and figures of reference marked thereon, which form a part of this specification.

10 The present invention relates to trunks that are to be used for carrying fragile articles; and it has for its object to so construct the trunk-box or body of the trunk that the trays which are ordinarily used in such trunks to carry the 15 fragile articles shall not come in contact with the rigid walls of the trunk, but with elastic projections from such walls; and it consists of the improved devices for that purpose herein described and claimed.

20 In the accompanying drawings, Figure 1 is a perspective view, and Fig. 2 a detail view, of a trunk-box embodying my invention, parts being broken away.

A A A are the vertical walls of a trunk-box, which are made in any usual way. B B B are tubular strips of soft elastic rubber, of any desired diameter sufficient to hold the trays from contact with the rigid vertical walls of the trunk. These tubular strips are secured 30 vertically, as shown, to the inner surfaces of the vertical walls of the trunk-box, preferably two to each of the four vertical walls. Each tubular strip is secured to the wall of the trunk-box by tacks all along the length of the strip, which hold the nearer side of the rubber tube fast to the wall of the trunk. This is readily accomplished by cutting a small hole through the opposite side of the rubber tube, through which the tack-head will pass and the 40 hammering can be done. At its top end both thicknesses of the tubular rubber strip are tacked down fast to the wall of the trunk, (forming a bevel or taper, as shown at a a,) and may be bent over and tacked down to the top 45 edge of the wall of the trunk. Each tubular strip is still further secured to the wall of the trunk-box, and held in place by covering-strips of canvas, b b, which are secured by suitable paste or glue both to the rubber tubes 50 and to the walls of the trunk-box, snugly holding the rubber tubes down in place and somewhat stiffening them. The trunk-box is then

finished by being covered on the outside and lined on the inside in the usual way, the lining snugly covering the rubber tubes as the canvas strips do, and assisting in holding the tubes in place. 55

C is a tray, of which there may be several, adapted in the usual way to rest upon the bottom of the trunk, or upon suitable steps, or 60 upon each other.

The operation of my improved device is as follows: The tray C is put in place in the trunk in the usual way. In moving downward to its seat it touches at its sides and ends the covered 65 tubular strips B B B only, for which it is made just a comfortable fit in the usual way, and when in its seat it is held in place by these tubular strips taking against its sides and ends, and when the loaded trunk is tossed 70 about, as it is liable to be in use, the tubular strips take up the sidewise motion of the tray within the trunk, and keep the tray from striking or jarring against the rigid vertical walls of the trunk. 75

I prefer the particular construction of devices shown in the drawings. The bevel at the upper end of the strips assists in the convenient placing of the tray in the trunk. So also does the vertical arrangement of 80 the strips and the particular number of the strips and their arrangement opposite each other, as shown in the drawings. So also does the employment of tubes of rubber or half tubes or strips of triangular cross-section with an edge operative, as distinguished from flat strips; but my invention is not limited to any one of these specific details. I also prefer to secure the rubber strips to the walls of the trunk in the manner and by the means shown; but the re-enforcing canvas strips b b 85 may be omitted and any suitable means employed of securely fastening the rubber strips to the walls of the trunk, so that they become practically an integral part of the trunk-walls 90 and the part against which the sides or ends, or both, of the tray bear when the tray is in place and the trunk in use. 95

The bevel or taper at the upper end of the rubber strip may be produced by cutting or forming the rubber itself at that point to a bevel, as well as by forcing it to a bevel, as shown.

While I prefer to use two tubular strips of

rubber on each of the four vertical walls of the trunk, still my invention as recited in the first clause of claim would be embodied and its advantages in part enjoyed if but one—as, say, a central strip—were used, and on but one wall of the trunk, the tray being made a snug fit for the trunk-body so lined.

It is an advantage of my preferred form having two or more vertical strips on opposite walls that any movement of the loaded trays in either direction is deadened and a rebound of the load thereby prevented, and thus both sets of strips co-operate to protect the opposite walls as well as to protect the tray, and, moreover, the tray is prevented from assuming a diagonal position in the trunk.

I am aware that springs of rubber have been used in crates for fruit and cans for explosives, as shown in patents granted to Doolittle and Carson, October 9, 1860, and J. Taylor, August 1, 1871, where the springs are attached to both the inside and the outside cases or cans, but do not form an integral part of either, and where the inner can or case is suspended on

such springs. I do not claim, broadly, the use 25 of a spring between the sides or ends of a trunk and its tray.

What I claim as new, and desire to secure by Letters Patent, is—

1. As an article of manufacture, a trunk for 30 fragile articles, having one or more tubular strips of rubber secured to and forming a part of the vertical walls, one or more, of the trunk on the interior, whereby the tray is held from contact with the rigid wall of the trunk, substantially as and for the purposes set forth.

2. As an article of manufacture, a trunk for fragile articles, having two or more tubular strips of rubber secured vertically to and forming a part of the opposite vertical walls of the 40 trunk on the interior, whereby the tray is held in place and kept from contact with the rigid walls of the trunk, and said walls are protected, substantially as and for the purposes set forth.

JNO. D. CROUCH.
